SHARPENING DEVICE FOR SCISSORS

Tindaro A. Calabrese, Woodside, N. Y.

Application April 22, 1946, Serial No. 664,030

4 Claims. (Cl. 51—69)

1

This invention relates to sharpening devices and in particular to one employed for honing or sharpening scissors or shears.

A particular object of the invention is to provide a compact and readily adjustable sharpening device that can be mounted on the edge of a work bench and which includes as a part of the combination a manually operable stone.

A still further object of the invention is to provide a guide for the sharpening stone which may be adjusted so that the stone will assume the proper angle and be maintained in such position for sharpening the scissors with the proper beveled edge.

Still further objects of the invention are, to provide means for mounting the guide member so that it can be adjusted to any desired angle; to provide on the shears holder or blade supporting portion of the device adjustable means whereby the work may be raised or lowered to coincide with the angle at which the honing stone or implement is held; to provide a sharpening device having a minimum number of parts that will afford a maximum adjustment and one in which the adjustable features may be manipulated with a minimum of effort.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure—

Fig. 1 is a view in perspective of a sharpening device illustrating scissors or shears in position therein.

Fig. 2 is a side elevational view of Fig. 1 having portions thereof broken away to more clearly illustrate details of construction.

Fig. 3 is a view in elevation looking from the left at Fig. 2.

Fig. 4 is a view in elevation looking from the right at Fig. 2.

Referring to the drawings in detail 10 indicates a bench or other support upon which the sharpening device is mounted. The latter includes a bracket 35 having a base portion 12 attached to the bench 10 by several rivets 35a.

The bracket 35 has a vertical guide post 36 and a vertical blade post 37, the guide post 36 having supported, at the upper edge thereof on a hinge pin 34, an adjustable guide head 38, which is formed to provide the spaced longitudinally extending flanges 39 which are wide enough to pro-

2

vide a slot in the adjustable guide head as at 40, in which the handle bar 18 of the sharpening implement 19 slides. The width of the slot 40 is equal to the thickness of the handle bar 18 so that the bar will be supported at the desired angle to be reciprocated manually without any attention on the part of the operator as to whether or not the stone is sharpening the blade at the proper angle. The adjustable guide head 38 is provided with the ears 41 which abut ears 42 formed on the upper end of the guide post 36 and the end of the hinge pin 34 is threaded to receive the wing nut 43 by which the guide head 38 may be held in any adjusted position as indicated in outline in Fig. 2.

The blade post 37 of the bracket 35 is slotted as at 45 and provided with the side ears 46 in which are adjustably mounted for sliding movement, the lower ends 47 of a pair of bracket clamps 48 and 49. The lower ends 47 of said clamps are frictionally secured at any vertical adjusted position to the blade post 37 by the use of the bolt and nut arrangement 50. The upper ends of the clamps are also brought forcibly toward each other to hold the cutting edge 20 of a scissor blade 21 in position by the use of a bolt and nut arrangement 51 about the bolt of which spring 52 is used to urge the clamps apart. It is evident therefore, that by these adjustable features as used in connection with the blade holder and the stone guide means, any desired angle of grind of the blade may be obtained and that either the blade holder or the stone guide may be individually adjusted to suit the conditions desired.

While I have referred to the use of the device for the purpose of sharpening scissors and shears it is to be understood that the features of the invention may be employed in a device for sharpening any implement such as knives or the like.

It is to be understood that if desired, the guide, which is used for supporting the sharpening or honing stone, may be constructed of any suitable horizontal plate or bar without the use of the guide slot previously shown.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A sharpening device having a bracket for attachment to a fixed support and a clamp at one end thereof for supporting an article with its edge to be sharpened in a horizontal plane so that a honing implement may be moved longitudinally of the edge for sharpening the same, means on the bracket to be engaged by a handle bar of the honing implement for guiding movements of the honing implement longitudinally of the edge, comprising a guide post extended vertically from said bracket at a point spaced from the clamp, a guide head formed with an elongated slot in a horizontal plane through which the handle bar of the honing implement passes, ears extended vertically from the top edge of said guide post, ears depended vertically from the bottom edge of said guide head and overlapping the ears of said guide post, means engaged through the overlapped ears for holding the guide head in various angular adjusted positions relative to said guide post, and means extended from the top and bottom edges of the material of said guide head defining said slot for engaging the top and bottom faces of the handle bar of the honing implement for adjusting the angular position of the honing implement as the angular position of the guide head is adjusted.

2. A sharpening device having a bracket for attachment to a fixed support and a clamp at one end thereof for supporting an article with its edge to be sharpened in a horizontal plane so that a honing implement may be moved longitudinally of the edge for sharpening the same, means on the bracket to be engaged by a handle bar of the honing implement for guiding movements of the honing implement longitudinally of the edge, comprising a guide post extended vertically from said bracket at a point spaced from the clamp, a guide head formed with an elongated slot in a horizontal plane through which the handle bar of the honing implement passes, ears extended vertically from the top edge of said guide post, ears depended vertically from the bottom edge of said guide head and overlapping the ears of said guide post, means engaged through the overlapped ears for holding the guide head in various angular adjusted positions relative to said guide post, and means extended from the top and bottom edges of the material of said guide head defining said slot for engaging the top and bottom faces of the handle bar of the honing implement for adjusting the angular position of the honing implement as the angular position of the guide head is adjusted, said second-mentioned means comprises a hinge pin engaged through said overlapped ears and having a head at one end and having its other end threaded, and a wing nut threadedly engaged upon the threaded end of said hinge pin.

3. A sharpening device having a bracket for attachment to a fixed support and a clamp at one end thereof for supporting an article with its edge to be sharpened in a horizontal plane so that a honing implement may be moved longitudinally of the edge for sharpening the same, means on the bracket to be engaged by a handle bar of the honing implement for guiding movements of the honing implement longitudinally of the edge, comprising a guide post extended vertically from said bracket at a point spaced from the clamp, a guide head formed with an elongated slot in a horizontal plane through which the handle bar of the honing implement passes, ears extended vertically from the top edge of said

guide post, ears depended vertically from the bottom edge of said guide head and overlapping the ears of said guide post, means engaged through the overlapped ears for holding the guide head in various angular adjusted positions relative to said guide post, and means extended from the top and bottom edges of the material of said guide head defining said slot for engaging the top and bottom faces of the handle bar of the honing implement for adjusting the angular position of the honing implement as the angular position of the guide head is adjusted, said latter-mentioned means comprises flanges extended laterally from one side of said guide head above and below said slot.

4. A sharpening device having a bracket for attachment to a fixed support and a clamp at one end thereof for supporting an article with its edge to be sharpened in a horizontal plane so that a honing implement may be moved longitudinally of the edge for sharpening the same, means on the bracket to be engaged by a handle bar of the honing implement for guiding movements of the honing implement longitudinally of the edge, comprising a guide post extended vertically from said bracket at a point spaced from the clamp, a guide head formed with an elongated slot in a horizontal plane through which the handle bar of the honing implement passes, ears extended vertically from the top edge of said guide post, ears depended vertically from the bottom edge of said guide head and overlapping the ears of said guide post, means engaged through the overlapped ears for holding the guide head in various angular adjusted positions relative to said guide post, and means extended from the top and bottom edges of the material of said guide head defining said slot for engaging the top and bottom faces of the handle bar of the honing implement for adjusting the angular position of the honing implement as the angular position of the guide head is adjusted, said latter-mentioned means comprises flanges extended laterally from one side of said guide head above and below said slot, and a honing implement having a handle bar sliding in the slot of said guide head between said flanges, said slot being of a width equal to the thickness of the handle bar so that the flanges will engage the top and bottom faces of the handle bar and said flanges being coextensive with said slot to engage the top and bottom faces of said handle bar at all positions along the length of said slot.
